UNITED STATES PATENT OFFICE.

HENRY N. EDENS, OF NEW HOLSTEIN, WISCONSIN, ASSIGNOR TO THE JOHN LAUSON MANUFACTURING COMPANY, OF NEW HOLSTEIN, WISCONSIN.

DESIGN FOR A GAS-ENGINE CASING.

42,962.

Specification for Design.

Patented Sept. 3, 1912.

Application filed June 28, 1912. Serial No. 706,498. Term of patent 14 years.

To all whom it may concern:

Be it known that I, HENRY N. EDENS, a citizen of the United States, residing at New Holstein, in the county of Calumet and State of Wisconsin, have invented a new, original, and ornamental Design for Gas-Engine Casings, of which the following is a specification, reference being had to the accompanying drawings, forming part thereof.

In the drawings, Figure 1 is a side elevation of a gas engine casing illustrating my new design; Fig. 2, a plan view of the

same; Fig. 3, a front end view of the casing, and Fig. 4, a rear end view of said casing. I claim:

The ornamental design for a gas engine casing as shown.

In testimony that I claim the foregoing I have hereunto set my hand at New Holstein in the county of Calumet and State of Wisconsin in the presence of two witnesses.

H. N. EDENS.
